(57) **CLAIM**

The ornamental design for a security tag, as shown and described.

DESCRIPTION

FIG. 1 is a top right perspective view of a security tag in accordance with a first embodiment of my new design, in a collapsed mode;

FIG. 2 is a top right perspective view of the security tag of FIG. 1, in an expanded mode;

FIG. 3 is a top plan view of FIG. 1 or FIG. 2;

FIG. 4 is a right-side elevational view of FIG. 1 (left-side elevational view is mirror image);

FIG. 5 is a right-side elevational view of FIG. 2 (left-side elevational view is mirror image);

FIG. 6 is a rear elevational view of FIG. 1;

FIG. 7 is a rear elevational view of FIG. 2;

FIG. 8 is a top right perspective view of a security tag in accordance with a second embodiment of my new design, in a collapsed mode;

FIG. 9 is a top plan view of FIG. 8;

FIG. 10 is a bottom plan view of FIG. 8 (and also FIG. 12);

FIG. 11 is a right-side elevational view of FIG. 8 (left-side elevational view is mirror image);

FIG. 12 is a right-side elevational view of the security tag of FIG. 8, in an expanded mode (left-side elevational view is mirror image);

FIG. 13 is a rear elevational view of FIG. 8; and,

FIG. 14 is a rear elevational view of FIG. 8, in an expanded mode (as in FIG. 12).
